UNITED STATES PATENT OFFICE.

WILLIAM P. WARE, OF ALDERSON, WEST VIRGINIA.

RAILROAD STREET AND ROAD CROSSING.

1,390,182.

Specification of Letters Patent.

Patented Sept. 6, 1921.

Application filed May 13, 1921. Serial No. 469,251.

To all whom it may concern:

Be it known that I, WILLIAM P. WARE, a citizen of the United States, residing at Alderson, in the county of Monroe and State 5 of West Virginia, have invented certain new and useful Improvements in Railroad Street and Road Crossings, of which the following is a specification.

The present invention relates to railroad 10 construction, and more particularly to the construction of railroads at street and public highway intersections.

An object of the present invention is to provide a crossing of this type which is durable and which does not require frequent repair and is not subject to objections as to 15 pockets, projections and other portions with which the feet, wheels and other objects may be caught.

Another object of the invention is to provide a railroad crossing of this type wherein the ballast or filling placed between the rails, ties and other parts of the structure may be maintained compact and held from disintegration 20 incident to the passage of road vehicles thereover.

The invention further aims at the provision of an improved approach plate adapted not only to maintain the ballast but to 25 also facilitate transportation over the crossing and to prevent animals from slipping in approaching the track, particularly when the parts are coated with snow and ice.

A still further object of the invention is 30 to provide a novel form of guard rail which may be interlocked with the main line rail and which depends in part upon the main rail for sustaining the guard rail in a definite fixed position with respect to the main rail.

This object also embraces features of support for the main rail which are adapted to 35 accommodate light and heavy rails according to substitution and replacement incident to wearing down of the main rails.

The above and various other objects and 40 advantages of this invention will be in part described in and in part understood from the following detailed description of the present preferred embodiment, the same being 45 illustrated in the accompanying drawings wherein:—

Figure 1 is a top plan view of a railroad street and road crossing constructed according to the present invention.

Fig. 2 is an enlarged transverse section taken through the same at one main rail.

Fig. 3 is a fragmentary top plan view of a portion of the guard rail showing the means for accommodating rails of different weights for interlocking engagement with 60 the guard rail.

Fig. 4 is a fragmentary enlarged side elevation of the end of the guard rail interlocked with the main rail, and showing a cross plate in assembly therewith. 65

Fig. 5 is a fragmentary perspective view of the guard rail and an approach plate in their relative positions ready to be assembled upon the opposite sides of a main rail, and

Fig. 6 is a detail perspective view of one 70 end of a cross plate, showing the interlocking tongue for engagement beneath the main rail.

Referring to the drawings by numerals, 10 and 11 designate main line rails of usual 75 construction having a vertical web portion 12 and a base portion 13. At the inner sides of the rails 10 and 11 and at street or highway intersections are disposed guard rails 14, best shown in Fig. 2. Each guard rail 80 14 comprises an upstanding web portion 15 having a head or ball on its upper edge extending a height substantially one-half inch below the horizontal plane of the ball of the main rail 10. The head or ball of the 85 guard rail has a sloping or diagonal face 16 disposed oppositely from the main rail 10 and adapted to ward off obstacles coming in contact with the guard rail and prevent catching or hooking of such articles either 90 on the guard or main rails.

The web 15 is provided at its lower edge portion with a plurality of suitably spaced apart supporting plates 17 which project in the direction of the rail 10 and which are 95 adapted to extend therebeneath for supporting the main rail and also for interlocking the guard rail thereto. The web 15 of the guard rail is also provided at its ends constituting the terminals of the guard rail at 100 opposite sides of the crossing, with inwardly flanged wings or web portions 18 projecting over the base 13 of the main rail and having an upper edge portion laterally enlarged and merging out of the ball or head of the guard 105 rail. The upper edge portion of the web 18 is beveled downwardly as at 19 from the top of the guard rail to form an inclined deflecting and supporting surface such as is shown to advantage at Fig. 4. 110

Each plate 17 is adapted to rest upon the upper face of a tie 20 and be secured thereto

by spikes. The free ends of the plates 17 project beyond the remote edge of the base 13 of the main rail sufficiently to expose a spike opening 21 for the reception of a spike 22 when a like rail is installed and for exposing an outer spike opening 23 to receive the spike 22 when a heavier rail is used. By the provision of this extension and these spike openings, thus arranged, the 10 guard rail is adapted for installations of light and heavy rails and is also adapted for renewal of rails of different weights than was primarily installed.

For further supporting the guard rail 14, 15 the web of the latter is provided with a plurality of spaced apart foot portions 24 preferably forming extensions of the plates 17 and adapted to lie flat upon the ties 20 at the outer sides of the guard rails. Each foot 20 24 is provided with a single spike opening 25 adjacent the base of the web 15 and is provided with a pair of spaced apart spike openings 26 near the outer edge portion of the foot. By means of this arrangement the 25 foot 24 is maintained from breaking off at its juncture with the web 15 and at the same time the guard rail is effectively maintained in interlocking engagement with the main rail.

30 At each end of the crossing there is provided a cross plate 27 which is arranged at an inclination corresponding to the angle of the beveled edge 19 at the end of the guard rail, and the ends of the cross plate 35 27 are adapted to rest and be supported upon the ends of the opposite guard rails and held thereto by spikes 28 which are driven through the outer flange 29 of the plate 27 and into an adjacent tie 20. From Fig. 4 it 40 will be noted that the flange 29 constitutes the lower or outer edge of the plate 27 and that the flange is substantially horizontal to lie flat upon the upper face of the tie. The flange 29, as shown in Fig. 6 is provided with any desired number of spike receiving openings 30 through which spikes may be driven for anchoring the cross plate 45 in position.

The crossing is provided at opposite sides 50 with approach plates located at the outer sides of the main rails 10 and 11, and each approach plate comprises a relatively flat body portion 31 having on its outer edge a base flange 32 adapted to extend across the 55 ties 20 and be secured thereto by spikes in the manner of securing the cross plate 27. The body portion 31 rises at a suitable inclination toward the top of the main rail 10 and terminates in closely spaced relation 60 thereto and at a suitable point below the plane of the tread thereof. The upper face of the approach plate 31 is provided with one or more longitudinal extending grooves or serrations 33 with which the feet of draft 65 animals and the like may engage to prevent

slipping when approaching the crossing. The approach plate 31 is provided upon its under side with a plurality of depending webs 34 terminating at their lower ends in tongues 35 projecting inwardly from the 70 flange 32 beneath the webs 34 and extending beyond the latter for interlocking engagement beneath the base 13 of the main rail. The inner lower corners of the webs 34 are recessed as at 36 for the reception of the adjacent longitudinal edge portion of the base 13 so that the approach plate is supported not only upon the ties 20 but also upon the base of the main rail.

From Fig. 6 it will be noted that the cross plate which is used between the main rails is provided with a tongue 37, and such tongue formation is upon opposite ends of the cross plate so as to interlock the latter beneath the base of the rail and not only hold the cross plate to the tie 20 by the spikes 28 but also by use of the tongues 37.

The structure thus described after installation is packed in the usual manner with ballast and the usual road covering so as to provide a relatively smooth and uninterrupted crossing which cannot clog up the spaces between the guard and main rails. At the same time the cross plates 27 are so arranged and sloped that brakemen and other employees working on the tracks cannot interlock their feet with the guard rails and other parts of the crossing as has been the case heretofore.

It is of course understood that various 100 changes and modifications may be made in the details of construction and design of the above specifically described embodiment without departing from the spirit of this invention, such changes and modifications 105 being restricted only by the scope of the following claims.

What is claimed is:

1. In a railroad street crossing the combination with the main rails, guard rails arranged at the inner sides thereof, cross plates arranged between the main rails at opposite ends of the guard rails, and approach plates disposed at opposite sides of the crossing and at the outer sides of the main rails.

2. In a railroad street crossing, the combination with the main rails, guard rails interlocked with the main rails and arranged at the inner sides thereof and having outwardly sloping end flanges, cross plates arranged between the main rails and seated at their under sides upon said flanges, and approach plates located at opposite sides of the main rails, said approach plates having interlocking portions engaging the base flanges of the main rails and having tie engaging portions at their outer ends.

3. A railroad street crossing comprising a pair of guard rails adapted for interlock-

ing engagement at the inner sides of the main rails, cross plates adapted to be seated on the opposite ends of the guard rails and having interlocking tongues for engagement 5 with the main rails, and approach plates provided with interlocking portions adapted to engage the outer sides of the main rails for uniting the main rails, the guard rails and the approach plates in a unitary structure with the cross plates.

4. A railroad street crossing comprising a pair of guard rails adapted to be placed at the inner sides of the main rails and having

outstanding plates at their lower ends adapted to engage beneath the main rails and having foot pieces extending inwardly for attaching the guard rails to ties, cross plates interlocked with the main rails across the ends of the guard rails for inclosing the space therebetween, and approach plates 15 adapted to be interlocked with the outer sides of the main rails for warding off objects from contact with the main rails.

In testimony whereof I affix my signature.

WILLIAM P. WARE.
